BLEACHER REST MEMBER

Application filed May 16, 1930. Serial No. 452,953.

This invention pertains to an improvement in portable or knock-down seats or bleachers, and more particularly in bleachers of the circus-seat type wherein independently removable rest members are used in tiers and supported by a collapsible or knock-down skeleton frame including inclined stringers or beams. In the old structures known to me the rest members comprising independent seat and foot boards, are usually placed in overlapping relation at their ends and held loosely in place on brackets or hangers secured to the stringers. The object of the present invention is to provide quickly detachable means for securing the abutting ends of two rest members together and at the same time connect the same pivotally or with a limited free play to a supporting bracket or hanger on an inclined stringer or beam forming a part of the skeleton structure or bleacher frame. A strong and durable attachment for the rest members is thereby provided, and the connections thus made serve to brace and strengthen the upper part of the structure as a whole and to distribute the load uniformly to the trestle work or jacks used at spaced intervals to support the inclined stringers. The means for locking the rest members to the stringer brackets or hangers is also constructed in a particular way to prevent accidental disconnection of the parts, although made to detach easily when manually operated, all as herein shown and described and more particularly pointed out in the claims.

In the accompanying drawings, Fig. 1 is a side elevation of a portable bleacher embodying my improvement, and Fig. 2 is a sectional view vertically through the same looking rearwardly from line 2—2 of Fig. 1. Fig. 3 is an enlarged top or plan view of two seat boards hinged together and also pivotally connected to a supporting bracket mounted upon a stringer or beam, and Fig. 4 is a sectional view on line 4—4 of Fig. 3, showing the same parts. Fig. 5 is a sectional view on line 5—5 of Fig. 3, and Fig. 6 a front edge view of the seat boards and the supporting bracket looking inwardly from line 5—5 of Fig. 4. Fig. 7 is a perspective

view of one of the hinge members affixed to one end of a seat board.

The bleacher delineated in Figs. 1 and 2 corresponds closely to the structure shown and described in my co-pending application Serial No. 452,952, except for the board seats and brackets surmounting the inclined stringers or beams A. Thus, separate sets of trestle units, each composed of a plural number of jacks B mounted on longitudinally-extending sleepers C serve to support a series of stringers or beams A in the same inclined plane. The tops of the stringers or beams A are provided at spaced intervals with a plurality of upright brackets D to support separate removable seat boards E while other brackets or hangers F are suspended from the bottom face of the stringer to support foot boards G. The jacks B in the respective rows of trestle units, from front to rear of the structure, are coupled together by tie rods H, and with the present improvement all or any desired number of stringers A are connected together longitudinally of the structure, that is, parallel with the sleepers C, thereby connecting the upper ends of the jacks in each row together and thus bracing and connecting the successive trestle units placed end to end in each row.

Thus, each inclined stringer A is provided at its upper edge or top with upright brackets D, each one or any given number of which include a horizontal member 2 of metal riveted at one end to the side flanges 3 of the stringer or I-beam A, the opposite or front end 4 being bent at an angle and riveted to a vertical member or leg 5 also affixed by rivets to stringer A. The upper end of leg 5 extends upwardly beyond the horizontal member 2 and is provided with an elongated or key opening 6 adapted to permit the flattened or widened extremity 7 of a hinge pin or rod 8 to be inserted therethrough. An angular plate of metal 9 having a similar key opening 10 is secured to the rear or inner end of horizontal member 2, whereby the rear extremity 7 of hinge pin 8 may be inserted through plate 9 and interlocked therewith. That is, the pin will be locked against withdrawal when the pin is rotated a quarter of

a revolution to place its lateral projections or widened extremity 7 at right angles to the major axis of the elongated openings 6 and 10, see Figs. 3 and 4. The locking pin or rod 5 is bent downwardly at its front end at right angles to the plane of the flattened extremity 7, thus placing the balance of weight beneath the axis to hold the pin in a locking position by gravity after connecting the seat boards 10. E loosely together by means of the pin. A hinge connection is obtained by providing the end portions of two abutting seat boards D—D with complementary hinge members or connecting yokes 11, each of 15 which is of U-shape to receive and cover the wooden board and to permit bolts or rivets 12 to be used to fasten both legs or sides of each yoke to the board. These hinge or yoke members cover substantially the entire width 20 of the board and also a substantial part thereof inwardly from the end edge to re-enforce and protect the same and to prevent warping and splitting. Each yoke 11 includes an end connecting wall which is cut at uniformly spaced intervals and the stock pressed in opposite directions alternately to provide semi-circular or oval-shaped hinge loops 14—14' adapted to permit the flattened end 25 of the connecting rod or hinge pin 8 to pass therethrough. The outwardly-extending loops 14 on each hinge or yoke member may be nested within the inwardly pressed loops 14' of the other member, and the hinge pin 30 or connecting rod 8 may be readily inserted 35 through the nested portions to lock them pivotally together, as seen in Figs. 3 and 5. The weight of the board and its load is carried by the flat horizontal rest member 2 of the bracket, and the union between all the parts is sufficiently free and loose vertically to permit 40 rotatable movement of the hinge members and vertical play in respect to the hinge pin or rod 8. The seat boards, however, are thereby connected at their opposite ends to 45 each other and also to two stringers, either closely or remotely related as may be predetermined by the length of the board employed. Also, by providing a connection for the seat boards, as described, the boards will 50 rest in the same plane at the joint, and the flat yoke members and the rounded hinge connection permit the boards to be occupied directly above the joint without risk of injury to the clothing or discomfort to the person 55 sitting at that place. The bleacher structure is also stabilized and braced more rigidly as a whole by employing such a device, whether embodied in a bleacher of the kind shown and described in my companion application here referred to, or if incorporated in 60 a similar knock-down structure. Also, and obviously, the foot boards G and hanger brackets H may be constructed and connected together in the same way as the seat boards 65 E and brackets D, and the term "rest mem-

ber" as used herein designates either a seat board or a foot board.

What I claim, is:

1. A bleacher, comprising a skeleton supporting frame, and horizontal rest members having interengaging loop portions at their ends and secured in tiers detachably to said frame. 70

2. In a bleacher, inclined stringers having brackets, horizontal rest members having looped end connections, and means for coupling said end connections and simultaneously securing said members detachably to said brackets. 75

3. In a bleacher, an inclined stringer having a bracket affixed thereto, horizontal rest members having complementary yoke members at their abutting ends, and means for securing said complementary yoke members to each other and said bracket. 80

4. In a bleacher, a pair of horizontal rest members having looped connections, a bracket adapted to support said rest members jointly at their looped connections, and locking means for securing said rest members detachably to said bracket. 90

5. In a bleacher, a pair of horizontal rest members arranged end to end and provided with separable interengaging connections, a bracket adapted to support said rest members jointly, and a removable pin for said connections detachably interlocked with said bracket. 95

6. In a bleacher, a stringer having a bracket formed with openings, a pair of rest members having re-enforcing members at their abutting ends, said members having internesting loop portions, and a locking pin extending through said openings and loop portions to connect the parts together with loose play therebetween. 100

7. In a bleacher, a stringer having a bracket mounted thereon, a pair of rest members having U-shaped re-enforcing members secured to their abutting ends and formed with internesting loops, and a connecting pin detachably secured to said loops and said bracket. 110

8. In a bleacher, a stringer having a bracket, a pair of rest members having complementary members formed at their ends with internesting loops, and a removable connecting pin for said members having a locking connection with said bracket. 115

In testimony whereof I affix my signature. 120
JOHN B. PATTERSON.
